KEY FOR CYLINDER LOCKS

Edward N. Jacobi, Milwaukee, Wis., assignor to
Briggs & Stratton Corporation, Milwaukee,
Wis., a corporation of Delaware

Original application November 3, 1933, Serial No.
696,467. Divided and this application October
17, 1934, Serial No. 748,623

2 Claims. (Cl. 70—9)

This invention relates to improvements in keys for cylinder locks, and is a division of the co-pending application of Edward N. Jacobi, Serial No. 696,467, filed November 3rd, 1933.

It is an object of this invention to provide a key of novel construction, particularly adapted for cylinder locks having transverse oppositely projected tumblers.

Another object of this invention is to provide 10 a key of improved construction having both its edges bitted for engagement with tumblers of a cylinder lock and means intermediate the tumbler engaging edges for engagement with a key guiding rib extending down the keyway.

15 With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates two complete examples of the physical embodiment of the 25 invention constructed according to the best mode so far devised for the practical application of the principles thereof, and in which:

Figure 1 is a perspective view of a key embodying this invention;

Figure 2 is a cross section view taken through Figure 1 on the plane of the line 2—2;

Figure 3 is a perspective view illustrating a modified embodiment of this invention; and

35 Figure 4 is a front elevation of a cylinder lock with the key of this invention in place, and shown in cross section.

Referring now more particularly to the accompanying drawing, in which like numerals indicate like parts, it is seen that the key consists of a blade 5 connected to a head by a shank 7. The blade has a groove 8 extending longitudinally along one side for engagement with a key guiding bar or rib 9 extending down the keyway of a cylinder lock as shown in Figure 4, and more specifically brought out in the aforesaid copending application. The depth of this groove, as best shown in Figure 2, is greater than the major thickness of the blade and in fact almost cuts 45 the blade in two, so that the bar or rib 9 in the cylinder, by engaging the bottom 10 of the groove substantially divides the keyway into two chambers.

As shown in Figure 4, in which the outer cap 55 and dust cover are omitted for the sake of clarity,

the keyway of the lock cylinder is so shaped that its wall, at least at the mouth of the keyway opposite the key guiding bar, closely surrounds the bar and to keep the opening at the mouth of the keyway as small as possible, approaches close to the face of the keyway from which the key guiding bar projects.

Consequently, the thickness of the key blade directly above and beneath its groove 8, is thin, and in fact too thin to have good wearing ability 10 at its tumbler engaging edges 11. Hence, to provide the proper thickness at the outer tumbler engaging edges of the blade, the cross sectional shape of the blade above and beneath its longitudinal groove is taperingly increased as shown. 15 In this manner, the highest points on the key, which do the most work and receive the greatest wear, inasmuch as the tumbler springs of the tumblers acted on by the high points are compressed the maximum amount, have the widest 20 surfaces and lower tumbler engaging points, on which the wear is not as great, automatically are of less thickness.

The wall 10 of the groove forms in effect a ridge extending longitudinally along the side of 25 the key blade opposite the groove and it is observed that the rear face of this wall lies in the plane of the adjacent face of the handle or head 6.

On the opposite face of the key, the surfaces of 30 the blade are likewise flush with the adjacent face of the head 6, and as the major thickness of the blade is less than the depth of the groove 8, it follows that the head or handle is of greater thickness than any portion of the blade. The 35 shank 7, besides being thicker than the blade, also has greater width than the blade proper, to increase the strength of the key.

The possibility of picking a lock with which 40 the key is used, is reduced to a minimum as the restriction of the space within the keyway is such that it is impossible to operate a picking tool. Further protection against possible picking may be afforded by extending a fin from the key guiding rib completely across the keyway, and to 45 accommodate such fin, the key may be formed as shown in Figure 3, in which the bottom wall 12 of the groove 8 is longitudinally slotted as at 13 through its entire length.

In other respects, the key illustrated in Figure 50 3 is identical to that shown in Figures 1 and 2.

From the foregoing description, taken in connection with the accompanying drawing, it will be readily apparent to those skilled in the art to 55

which this invention appertains, that this invention provides a key of novel construction and one exceptionally well suited to cylinder locks in which transversely acting tumblers are actuated in opposite directions.

5 5 What I claim as my invention is:

- 10 1. A key for tumbler locks in which the tumblers extend transversely and are oppositely projected, and in which the keyway is divided into two parts by a key guiding rib extending longitudinally down the keyway, comprising a blade having bittings along both edges and having a central groove extending longitudinally along one face thereof to substantially divide the blade into two parts, and having its opposite face cut away at opposite sides of the groove to leave a thin walled connection between the two parts into which the blade is divided by the groove and to give the two parts of the blade a substantially triangular cross section, the bases of the triangular cross section forming the bitting edges of the key, and a handle portion of greater thickness than the blade connected to the blade by a shank of greater width and thickness than the blade.
- 15 20 25 2. A key for tumbler locks in which the tumblers extend transversely and are oppositely

projected and in which the keyway is divided into two parts by a key guiding rib extending longitudinally down the keyway and the wall of the keyway opposite the key guiding rib lies closely around the key guiding rib so as to leave but a thin space adjacent said rib to preclude the insertion of picking tools into the keyway, comprising, a blade having bittings along both edges and having a central groove extending longitudinally along one face thereof to substantially divide the blade into two parts and to slidably engage the key guiding rib of the lock, and having its opposite face cut away at opposite sides of the groove to leave but a thin wall connected between the two parts into which the blade is divided by the groove and said cut away portions being so shaped as to give the two parts of the blade a substantially triangular cross section with the inner portions thereof thinnest and the outer portions thereof which form the tumbler engaging edges thickest, with the highest points on said edges of maximum thickness, and lower points correspondingly thinner as determined by the taper of said triangular wall sections, and a handle portion at one end of the blade.
